1,994,562

NEOTHIAZOLOCARBOCYANINE DYE AND
METHOD OF PREPARING ITLeslie G. S. Brooker, Rochester, N. Y., assignor to
Eastman Kodak Company, Rochester, N. Y., a
corporation of New YorkNo Drawing. Application June 30, 1931,
Serial No. 548,025

17 Claims. (Cl. 260—44)

This invention relates to a new composition of matter and particularly to a new class of photographic sensitizing dyes and a method for their preparation.

5 Most ordinary photographic emulsions are comparatively indifferent to those colors of the spectrum of longer wave-length and for that reason various types of sensitizing dyes have been suggested for use. These may be incorporated in the emulsion, or employed in a sensitizing bath, in which the photographic film or plate is bathed. Many cyanine dyes have been described for this purpose containing the benzothiazole nucleus. Dyes containing the naphthothiazole nucleus are described in my co-pending applications, Serial Nos. 337,177 filed February 2, 1929, 435,104 filed March 12, 1930, 435,105 filed March 12, 1930, and dyes containing the thiazoline nucleus are described in my co-pending application Serial No. 460,548 filed June 11, 1930.

An object of the present invention is to provide a process for the preparation of photographic sensitizers of a new type containing the thiazole nucleus. These dyes may be termed neothiazolocarbocyanines, by analogy with neocyanine, which is thought to contain a similar linkage connecting its three heterocyclic nuclei. Another object of the invention is to provide such photographic sensitizing dyes as may be added to photographic emulsions or coated thereon as an overcoating, thereby increasing the spectral sensitiveness of the emulsion. Other objects will hereinafter appear.

The thiazole ring is usually numbered in the following manner, and this system of numbering is used in the present application:

40 The base 2-methylthiazole, or a substituted 2-methyl-thiazole, e. g. 2-methyl-4-phenylthiazole, may be converted into an alkylquaternary salt by heating it with, for instance, a dialkyl sulfate or an alkyl p-toluene sulfonate or an alkyl iodide. When the alkyl halides are used, quaternary alkyl iodides are produced which on treatment with ethylorthoformate and pyridine under appropriate conditions yield as a principal product thi-azolocarbocyanines.

If trialkyl ortho esters of carboxylic acids other than formic acid are employed in the condensation, thiazolocarbocyanines are obtained with substituent groupings attached to the central carbon atom of the three-carbon carbocyanine chain. For instance triethylorthopropionate yields 7-ethylthiazolocarbocyanines. These dyes are fully dealt with in my co-pending application Serial No. 619,962 filed June 29, 1932.

The 2-methyl thiazoles also yield such dyes as thiazoloiso-cyanines and thiazolo- ψ -cyanines. These are dealt with in my co-pending application Serial No. 619,960 filed June 29, 1932.

5 In the present case, dialkylsulfates and more especially alkyl p-toluenesulfonates are used for the preparation of the thiazole alkylquaternary salts, and these when treated with an excess of ethyl orthoformate in anhydrous pyridine yield the neothiazolocarbocyanines of the instant application in preponderating amounts. A small amount of simple thiazolocarbocyanine frequently accompanies the neothiazolocarbocyanine, but as a rule the latter dyes are less soluble than these simple thiazolocarbocyanines and can readily be isolated in a pure state.

10 Analytical results indicate that the molecule of neothiazolocarbocyanine contains three thiazole nuclei, in two of which the nitrogen atoms are in the pentavalent state. The dye is probably represented by one of the following formulæ:

I

II

In these formulæ A and B represents univalent atoms or groupings such as hydrogen, alkyl or aryl; R stands for alkyl and X represents a suitable acid radical such, for example, as the halides, p-toluenesulfonate, alkylsulfate or in fact any suitable acid radical which will not greatly decrease or destroy the sensitizing properties of the dye, this radical being necessary to give electrical neutrality to the molecule. In the claims the phrase—"a suitable acid radical"—is employed to designate this group of acid radicals.

50 In Formula I, one molecule of ethylorthoformate is supposed to have reacted with three molecules of quaternary salt, whilst Formula II may be arrived at by supposing that two mole-

cules of ethylorthoformate react with three molecules of the alkyl quaternary salt. For various reasons, it is thought that Formula II is the more probable one, and the analytical evidence favors it in most cases. In any event, the utility of my invention is not affected by theoretical considerations relating to the exact structure of the molecule.

I will now give several examples for preparing various neothiazolocarbocyanines from the corresponding 2-methylthiazoles. However, it will be understood that they are merely representative of a great number of methods in which the proportions given and the equivalents used may vary for the particular type of dye required. My invention, therefore, will not be restricted thereby except as indicated in the appended claims.

PREPARATION OF NEOTHIAZOLOCARBOCYANINES

20

Step I

The thiazole base containing a reactive methyl group is first converted into an appropriate alkyl quaternary salt, by heating with, for instance, an alkyl sulfonic ester, such as an alkyl p-toluenesulfonate. The dialkyl sulfates may also be employed, but the yields are usually lower.

35 A and B are hydrogen atoms or substituent atoms or groups, R stands for alkyl and X stands for a suitable acidic radical such as p-toluenesulfonate ($-O.SO_2.C_6H_7$) or alkyl sulfate ($-O.SO_2.OR$)

Step II

40 The thiazole alkyl quaternary salt is heated in anhydrous pyridine with ethyl orthoformate (conveniently employed in excess) and dye formation occurs. This is most probably represented as follows:

50 (In the above formulae, Et represents the ethyl group C_2H_5). The dye may be isolated at this stage or it may be isolated as a more sparingly soluble salt in Step III.

Step III

55 This is a simple step and consists of double decomposition. The reaction mixture, concentrated or otherwise, or the solution of the dye in some other solvent is treated with an aqueous solution of an alkali salt of the acid whose anion it is desired to introduce into the dye. For instance, the p-toluene sulfonate of a dye may be treated with an aqueous solution of potassium iodide or sodium iodide or ammonium bromide. This alkali salt is conveniently employed in considerable excess. The dye iodides, for example, are usually fairly insoluble in cold aqueous solutions containing excess of inorganic iodide, and may therefore be conveniently obtained by filtration in the usual way.

Step IV

60 The crude dyes are finally purified, and this involves separation from the normal thiazolocarbocyanines which are usually formed simultaneously. In most cases these impurities are more soluble than the neothiazolocarbocyanines, but not invariably so. When the solubility relationship of the two dyes is established, separation may be effected using the methods of fractional crystallization.

65 The foregoing steps are illustrated in the following examples in which the dyes produced are named in accordance with my preferred general Formula II:

Example I

70 Iodide of the neothiazolocarbocyanine from 2-methylthiazole metho-p-toluenesulfonate 3,3'-dimethyl-7-[β -(thiazyl-2-methiodide)-vinyl]thiazolocarbocyanine iodide.

75 9.9 g. 2-methylthiazole (3 mols.) was heated with 18.6 g. methyl p-toluenesulfonate (3 mols.) on the steam bath. Addition took place rapidly and solidification appeared to be complete in about five minutes. The solid quaternary salt was dissolved in 150 cc. boiling dry pyridine and 16.5 cc. ethyl orthoformate (3 mols. 50% excess) added and the whole refluxed for five hours. On standing in the cold, crystals of the neothiazolocarbocyanine metho-p-toluenesulfonate separated. These were filtered off and washed with cold pyridine and then dissolved in boiling methyl alcohol and an aqueous solution of excess of potassium iodide in warm distilled water added and the mixture stood aside to crystallize out. The iodide of the dye so produced was filtered off and washed and the more soluble neothiazolocarbocyanine was removed by treatment with a hot mixture of acetone and methyl alcohol. The dye was purified by crystallization from methyl alcohol and was finally obtained as a dull purplish-black felted crystalline mass and gave a violet solution in methyl alcohol.

Example II

80 Iodide of the neothiazolocarbocyanine from 2-methylthiazole etho-p-toluenesulfonate 3,3'-diethyl-7-[β -(thiazyl-2-ethiodide)-vinyl]thiazolocarbocyanine iodide.

85 9.9 g. 2-methylthiazole (3 mols.) was heated with 20 g. ethyl p-toluenesulfonate (3 mols.) on an oil bath at 117-120° C. overnight. The crude 2-methylthiazole etho-p-toluenesulfonate was boiled under reflux with 40 cc. anhydrous pyridine and 22.2 cc. ethyl orthoformate (4 mols. 100% excess) for five hours. Most of the solvent was removed by concentration in vacuo and the residue was stirred with hot distilled water and

an excess of potassium iodide was added and the whole well mixed and stood aside to crystallize out. The dye was then filtered and washed. The residue was then dried and consisted of 5 greenish-bronze crystals apparently mixed with darker dull green crystals. The dye was boiled with acetone and filtered hot but the filtrate was quite bluish and little or no crimson thiazolocarbocyanine seemed to be present in the preparation. The dye was crystallized from methyl alcohol and gave beautiful greenish-bronze plates which imparted a violet coloration to methyl alcohol.

Example III

Iodide of the neothiazolocarbocyanine from 2,4-dimethyl-thiazole metho-p-toluenesulfonate 3,4,3',4' - tetramethyl - 7[β - (4 - methylthiazyl - 2 methiodide) - vinyl] - thiazolocarbocyanine iodide. 11.3 g. 2,4-dimethylthiazole (3 mols.) was heated on an oil bath at 115° C. with 18.6 g. methyl p-toluenesulfonate (3 mols.) for about an hour, solidification occurring within the first five minutes or less. The quaternary salt so obtained was refluxed for 4½ hours with pyridine (60 cc.) and 22.2 cc. ethyl orthoformate (4 mols.). During the reaction much solid separated. The reaction mixture was allowed to cool overnight and the p-toluenesulfonate of the dye was then 25 filtered off. The dye was converted into the iodide by boiling it with methyl alcohol and slowly stirring in a hot solution of potassium iodide in water. The whole was allowed to cool, and was then filtered and the dye washed. When 30 dried, the iodide of the dye consisted of a greenish-grey powder. Most of the more soluble crimson thiazolocarbocyanine was removed by boiling the dye with a mixture of methyl alcohol and acetone and filtering hot. The residue was 35 recrystallized from methyl alcohol and the dye, when air-dried, consisted of a felted mass of greenish-brown slender hairs and gave a violet-blue solution in methyl alcohol.

Example IV

Iodide of the neothiazolocarbocyanine from 2,4 - dimethyl - thiazole metho - methylsulfate 3,4,3',4' - tetramethyl - 7[β - (4 - methylthiazyl - 2 methiodide) - vinyl] - thiazolocarbocyanine iodide. 12.6 g. dimethylsulfate (3 mols.) was placed in a flask provided with a reflux condenser and 11.3 g. 2,4-dimethylthiazole (3 mols.) added in small portions down the condenser. This addition was accompanied by much heat evolution. The product was heated for a further hour at about 115° C. The crude quaternary salt was refluxed for 4½ hours with 60 cc. pyridine and 22.2 cc. ethyl orthoformate (4 mols.). At first two layers formed but these gradually merged during the course of the reaction. After standing for two days, solid separated in the reaction mixture. This was the methylsulfate of the dye and it was filtered off, washed, and dissolved in boiling methyl alcohol and the dye precipitated as the iodide by adding an excess of potassium iodide in hot distilled water. The dye was filtered off when cold and washed. The air-dried dye consisted of a greenish-grey powder. The crude dye contained the normal thiazolocarbocyanine, and this was mostly removed by boiling with methyl alcohol and filtering hot. The dye was then recrystallized from more methyl alcohol and consisted of a felted mass of dark greenish-brown needles which imparted a violet-blue coloration 75 to the solvent.

Example V

Iodide of the neothiazolocarbocyanine from 2,4 - dimethyl-thiazole etho-p - toluenesulfonate 4,4' - diphenyl-3,3' - diethyl-7[β - (4-methylthiazyl - 2 ethiodide) - vinyl] - thiazolocarbocyanine iodide. 11.3 g. 2,4-dimethylthiazole (3 mols.) was heated overnight at 115-120° C. with 20 g. ethyl p-toluenesulfonate (3 mols.). The crude quaternary salt, which was a light brown viscous liquid, was refluxed for 5 hours with 40 cc. pyridine and 22.2 cc. ethyl orthoformate (4 mols.). The reaction mixture was concentrated in vacuo and the residue mixed with hot distilled water and an excess of potassium iodide added. The dye was allowed to crystallize out and was then filtered off and washed. The air-dried dye consisted of small, dark bluish-green crystals. The dye was boiled with methyl alcohol and stood to cool somewhat and was then filtered before it was quite cold. The dye left on the filter was almost pure normal thiazolocarbocyanine and consisted of small purple needles which gave a crimson solution. The mother liquor was concentrated somewhat and was then cooled in a freezing mixture. Bluish-green crystals of the neothiazolocarbocyanine iodide were obtained. The mother liquor and washings were again concentrated and a third crop of crystals obtained, and similarly a fourth and fifth crop. These crops consisted of tolerably pure neothiazolocarbocyanine.

The dye was crystallized from methyl alcohol into beautiful greenish needles which became dull on drying and which gave a violet-blue solution in methyl alcohol.

Example VI

Iodide of the neothiazolocarbocyanine from 2-methyl-4-phenylthiazole metho-p-toluenesulfonate 4,4' - diphenyl-3,3' - dimethyl-7[β - (4-phenylthiazyl - 2 methiodide) - vinyl] - thiazolocarbocyanine iodide.

8.8 g. of 2-methyl-4-phenylthiazole (3 mols.) was heated with 9.3 methyl p-toluenesulfonate (3 mols.) for forty hours at 120-125° C. The product, a viscous liquid, was refluxed for five hours with pyridine (30 cc.) and 11 cc. ethyl orthoformate (4 mols.). The dye was precipitated as a tar by adding an excess of potassium iodide dissolved in hot water. After standing to cool, and pouring off the aqueous liquor, the dye was stirred with some boiling acetone when it became crystalline and was cooled and filtered. The air-dried dye consisted of a purplish-brown crystalline powder. The crimson normal thiazolocarbocyanine was removed by boiling with a mixture of methyl alcohol and acetone. The dye was then recrystallized from methyl alcohol and when dried consisted of a dull greenish-brown powder. The color of the methyl alcoholic solution was blue.

Example VII

Iodide of the neothiazolocarbocyanine from 2-methyl-4-phenylthiazole etho-p-toluenesulfonate 4,4' - diphenyl-3,3' - diethyl-7[β - (4-phenylthiazyl - 2-ethiodide) - vinyl] - thiazolocarbocyanine iodide.

8.8 g. of 2-methyl-4-phenylthiazole (3 mols.) was heated for 65 hours at 110-125° C. with 10 g. ethyl p-toluenesulfonate (3 mols.). The product, which was a light brown viscous liquid, was refluxed for 5 hours with pyridine (20 cc.) and 11 cc. ethyl orthoformate (4 mols.). The dye was precipitated as the iodide by adding a hot

solution of an excess of potassium iodide in water and stood aside to cool. The dye was filtered off and as it was somewhat tarry it was boiled in acetone, cooled, and filtered. The dye when dried consisted of a dull bronze colored powder. The dye was boiled with a mixture of methyl alcohol and acetone and filtered hot, but the solution was quite blue, as though little or no normal thiazolocarbocyanine were present. The dye was finally crystallized from methyl alcohol and consisted of small coppery crystals which gave a blue solution in the solvent.

As previously indicated and from the foregoing examples it will be observed that the neothiazolocarbocyanines are produced by the condensation of thiazole alkyl quaternary salts, containing reactive methyl groups (2-methylthiazole alkyl quaternary salts) with ethyl orthoformate in some suitable solvent such as anhydrous pyridine. Analytical evidence suggests that 3 molecules of the quaternary salt condense together with one, or more probably two, molecules of ethyl orthoformate. However, not every salt will give suitable yields of the neothiazolocarbocyanines inasmuch as some, notably the iodides, give principally the normal thiazolocarbocyanines in most cases.

The dyes may also be described as a particular type of 7-substituted thiazolocarbocyanine. In this case the substituent is an alkyl quaternary thiazyl vinyl group. Vinyl is $\text{CH}_2=\text{CH}-$ and if one H of the CH_2- group is replaced by an alkyl quaternary thiazyl group linked through its 2 position we get the substituent grouping probably present in the neothiazolocarbocyanines.

What I claim as new and desire to secure by Letters Patent is:

1. A neothiazolocarbocyanine salt containing three thiazole nuclei and having the following structure

in which A and B represent hydrogen atoms, an aliphatic group or an aromatic radical of the benzene series, R represents an alkyl group and X represents a suitable acid radical.

2. A 3,3'-dialkyl-7[β (thiazyl-2 alkyl quaternary salt)vinyl]-thiazolocarbocyanine salt.

3. A 3,3'-dimethyl-7[β (thiazyl-2 methiodide)-vinyl]-thiazolocarbocyanine iodide.

4. A 3,3'-diethyl-7[β (thiazyl-2 ethiodide)-vinyl]-thiazolocarbocyanine iodide.

5. A 3,4,3',4'-tetralkyl-7[β (4-alkylthiazyl-2 alkyl quaternary salt)vinyl]-thiazolocarbocyanine salt.

6. A 4,4'-dimethyl-3,3'-diethyl-7[β (4-methylthiazyl-2 ethiodide)vinyl]-thiazolocarbocyanine salt.

7. A 4,4'-diaryl-3,3'-dialkyl-7[β (4-arylthiazyl-2 alkyl quaternary salt)vinyl]-thiazolocarbocyanine salt.

amine salt, the aryl groups being of the benzene series.

8. A 4,4'-diphenyl-3,3'-dimethyl-7[β (4-phenylthiazyl-2 methyl quaternary salt)vinyl]-thiazolocarbocyanine salt.

9. A 4,4'-diphenyl-3,3'-diethyl-7[β (4-phenylthiazyl-2 ethyl quaternary salt)vinyl]-thiazolocarbocyanine salt.

10. A process for the preparation of carbocyanine dyes which comprises condensing, under the influence of heat, three molecular proportions of a thiazole alkyl quaternary salt with ethyl orthoformate in the presence of an organic base which is a solvent for the reactants and which acts to bind acid eliminated from the quaternary salt as a result of the condensation.

11. A process for the preparation of carbocyanine dyes which comprises condensing, under the influence of heat, three molecular proportions of a thiazole alkyl quaternary salt with not more than two molecular proportions of ethyl orthoformate in the presence of an organic base which is a solvent for the reactants and which acts to bind acid eliminated from the quaternary salt as a result of the condensation.

12. A process for the preparation of carbocyanine dyes which comprises condensing, under the influence of heat, three molecular proportions of a thiazole alkyl quaternary salt with ethyl orthoformate in the presence of pyridine.

13. A process for the preparation of carbocyanine dyes which comprises condensing, under the influence of heat, three molecular proportions of a thiazole alkyl quaternary salt with not more than two molecular proportions of ethyl orthoformate in the presence of pyridine.

14. A process for the preparation of carbocyanine dyes which comprises condensing three molecular proportions of a thiazole dialkyl sulfate with ethyl orthoformate in the presence of an organic base which is a solvent for the reactants and which acts to bind acid eliminated from the quaternary salt as a result of the condensation.

15. A process for the preparation of carbocyanine dyes which comprises condensing three molecular proportions of a thiazole dialkyl sulfate with not more than two molecular proportions of ethyl orthoformate in the presence of an organic base which is a solvent for the reactants and which acts to bind acid eliminated from the quaternary salt as a result of the condensation.

16. A process for the preparation of carbocyanine dyes which comprises condensing three molecular proportions of a thiazole alkyl para-toluenesulfonate with ethyl orthoformate in the presence of an organic base which is a solvent for the reactants and which acts to bind acid eliminated from the quaternary salt as a result of the condensation.

17. A process for the preparation of carbocyanine dyes which comprises condensing three molecular proportions of a thiazole alkyl para-toluenesulfonate with not more than two molecular proportions of ethyl orthoformate in the presence of an organic base which is a solvent for the reactants and which acts to bind acid eliminated from the quaternary salt as a result of the condensation.

LESLIE G. S. BROOKER.

Certificate of Correction

Patent No. 1,994,562.

March 19, 1935.

LESLIE G. S. BROOKER

It is hereby certified that error appears in the printed specification of the above numbered patent requiring correction as follows: Page 1, after line 56, insert the following paragraphs:

The general name for I is 3,3'-dialkyl-7-(thiazyl-2 alkyl salt) methyl-thiazolo-carbocyanine salt and that for II is 3,3'-dialkyl-7-[β (thiazyl-2 alkyl salt) vinyl]-thiazolocarbocyanine salt. In these two general names consideration of atoms or groups A and B is omitted for the sake of simplicity. Since these new dyes are believed to be structurally related to the known dye neocyanine, it is logical to call them "neothiazolocarbocyanines" which has been done herein.

The quaternary alkyl thiazyl group which is linked through the vinylene chain in the above formulae, has the alkyl group and the acidic radical both linked to the nitrogen atom of the thiazyl nucleus. This nitrogen atom is numbered 3 but since it is the only position in this thiazyl nucleus for such linkage, the number need not appear in the name of the dye.; and that the said Letters Patent should be read with this correction therein that the same may conform to the record of the case in the Patent Office.

Signed and sealed this 30th day of April, A. D. 1935.

[SEAL]

LESLIE FRAZER,
Acting Commissioner of Patents.
